BALANCED LIFTING DEVICE

Carl E. Moore, Gary, Ind.

Application December 24, 1940, Serial No. 371,547

4 Claims. (Cl. 294—67)

This invention relates to a lifting device, and, in particular, to a device for lifting long heavy objects, such as mill rolls, which can conveniently be seized for removal only at one end.

Various types of lifting devices have been proposed heretofore for unbalanced loads, such as a mill roll engaged at one end only. Some of these, furthermore, have been provided with an adjustable counterpoise to insure the correct balancing of loads of different weights. It is an object of my invention, therefore, to improve generally upon lifting devices of this type and to provide a simple sturdy device which can be constructed at relatively low cost and yet serve its purpose effectively.

In a preferred embodiment of my invention, I provide a lifting device comprising a rectangular frame, having an arm projecting from one end adapted to engage the roll or other object to be lifted. The frame provides guideways along which a traveling counterpoise is movable. I provide means, preferably motor-driven, for adjusting the counterpoise along the ways to obtain proper counter-balancing for loads of various weights.

Further details and advantages of the invention will become apparent from the following complete description and explanation of the preferred embodiment, which refer to the accompanying drawing illustrating such embodiment. In the drawing,

Figure 1 is an elevation showing the lifting device for my invention engaging a mill roll adapted to be lifted thereby;

Figure 2 is a side elevation; and

Figure 3 is a transverse section taken substantially along the plane of line III—III of Figure 1.

Referring now in detail to the drawing, the lifting device of my invention indicated generally at 10 comprises a substantially rectangular frame or beam 11, which may conveniently be a one-piece casting, or may be fabricated from separate casting or wrought metal members. In any event, the frame comprises substantially horizontal members 12 and 13 and vertical posts 14 and 15 therebetween. The horizontal members 12 and 13 serve as guides for a traveling counterpoise 16.

The counterpoise 16 comprises a massive block of metal having rollers 17 journaled therein on shafts 18. As shown in the drawing, the rollers engage the inner faces of the horizontal members or guide-ways of the frame 11. Angle brackets 19 welded to the top and bottom of the counterpoise 16 on opposite sides of the guide-

ways, prevent lateral displacement of the counterpoise from the frame.

10 A bore 20 extends through the counterpoise 16 and the nuts 21 and 22 are seated in opposite ends thereof. The nuts are flanged so that they can exert pressure on the counterpoise in opposite directions respectively. A screw shaft 23 is journaled in bearings 24 in the vertical posts 14 and 15 and is threaded through the nuts 21 and 22. Thrust collars 25, secured to the shaft 23, engage the outer faces of the posts 14 and 15.

15 An arm or extension 26 extends laterally from the frame 11 and is provided with article engaging means adjacent to the end thereof. In the 15 illustrated embodiment of the invention, this means comprises a socket 27 adapted to receive the end of a mill roll such as that shown at 28. Any other type of article-engaging means may, of course, be substituted for the socket 27.

20 A gear motor 29 is connected to the screw shaft 23 through a coupling 30. The motor unit of the gear motor 29 is preferably reversible and may be controlled manually by suitable equipment (not shown) to operate the screw shaft 23 in either direction. It will be apparent that 25 rotation of the screw shaft 23 in one direction or the other causes one of the nuts 21, 22 to exert a force on the counterpoise 16, tending to move it along the ways 12, 13. The collars 25 furnish the reacting thrust necessary to move the counterpoise.

30 A web 31 extending upwardly from the top horizontal member 12 of the frame 11 is provided with an eye 32 adapted to receive a lifting means such as a crane hook 33.

35 It will be apparent that in use, the lifting device of my invention is brought up to the roll 28 endwise so that the socket 27 receives the end of the roll. During this manipulation, the counterpoise 16 is shifted to its extreme left end position as viewed in Figure 2, whereby the entire device 10 is substantially balanced when supported on the hook 33. When all is in readiness for the roll 28 to be lifted, the counterpoise 16 is 40 shifted to the right and the crane from which the hook 33 is suspended is taken up.

45 As the roll is lifted, the counterpoise 16 may be adjusted one way or the other to obtain accurate balancing of the lifting device as a whole with the roll attached. When the roll is deposited at the desired point, the counterpoise 16 is restored to its normal position substantially centralized with the center line of the eye 32.

50 It will be apparent that the invention is characterized by numerous advantages. In the first

place, the construction is simple yet sturdy, so that the device can be designed for lifting heavy loads without running the cost thereof up to excessive amounts. The control of the counterpoise is readily effected by a gear motor of small capacity because of the rollers 18 which constitute an antifriction bearing between the counterpoise and its guides. Since the counterpoise moves longitudinally of the lifting device as a whole, the moment exerted thereby is directly proportional to the distance of the counterpoise from the line of support, in other words, a 1" shift of the counterpoise along its ways effects the same change in tilting moment regardless of the position of the counterpoise. In lifting devices using pivoted counterweights, the change in tilting moment effected by a predetermined angular movement of the counterweights depends on the initial position thereof.

Although I have illustrated and described but a preferred embodiment of the invention, it will be understood that changes in the construction and arrangement illustrated may be made without departing from the spirit of the invention or the scope of the appended claims.

I claim:

1. A device for lifting a long heavy object by one end comprising a generally rectangular frame providing spaced, horizontal ways, an arm extending from one end of said frame having means adapted to detachably engage said object, a coun-

terpoise adapted to travel on said ways, a motor mounted on said arm and means driven by said motor for actuating said counterpoise along said ways.

5. 2. A lifting device comprising a generally rectangular frame providing spaced, horizontal ways, and spaced, vertical posts, an arm extending from one end of the frame adapted to engage an object to be lifted, a counterpoise movable along said ways, and a screw shaft journaled in said posts for moving the counterpoise.

10 3. A lifting device comprising a generally rectangular frame providing spaced, horizontal ways, and spaced, vertical posts, an arm extending from one end of the frame adapted to engage an object to be lifted, a counterpoise movable along said ways, a screw shaft journaled in said posts for moving the counterpoise, and a motor mounted on said arm connected to said shaft.

15 4. A lifting device comprising a generally rectangular frame providing spaced, horizontal ways, and spaced, vertical posts, an arm extending from one end of the frame adapted to engage an object to be lifted, a counterpoise movable along said ways, a screw shaft journaled in said posts for moving the counterpoise, and nuts adapted to exert forces on said counterpoise in opposite directions, said shaft being threaded through said nuts.

CARL E. MOORE.
